UNITED STATES PATENT OFFICE.

ROSE HELLER, OF PHILADELPHIA, PENNSYLVANIA.

SCREEN.

1,093,779.

Specification of Letters Patent. Patented Apr. 21, 1914.

Application filed September 16, 1913. Serial No. 789,973.

To all whom it may concern:

Be it known that I, ROSE HELLER, a citizen of the United States, residing at Philadelphia, in the county of Philadelphia and State of Pennsylvania, have invented certain new and useful Improvements in Screens, of which the following is a specification.

My invention relates to improvements in screens, and more particularly to screens adapted to be positioned in front of a window to protect the occupants of the room from the gaze of those outside without materially excluding light or preventing ventilation.

A further object is to provide an improved screen of this character which may be readily placed in position, which may be readily folded into small compass when not desired, and securely locked when so folded.

With these and other objects in view, the invention consists in certain novel features of construction and combinations and arrangements of parts as will be more fully hereinafter described and pointed out in the claims.

In the accompanying drawings: Figure 1 is a view in elevation illustrating in full lines my improved screen in extended operative position, and in dotted lines showing the position of the parts when folded. Fig. 2 is a view in transverse section on the line 2—2 of Fig. 1. Fig. 3 is an enlarged fragmentary side elevation illustrating my improved locking means for the pivoted arms which securely hold the screen in folded position, and Fig. 4 is a view in section on the line 4—4 of Fig. 3.

1 and 2 represent parallel rods, the former longer than the latter and adapted to be positioned in screw eyes 3 in the wall or other support, and held against longitudinal movement by a pin 4 through the rod 1. The rods 1 and 2 are connected by two pairs of pivoted links 5, said links having elbow joints 6 at their meeting ends which limit the pivotal movement in one direction, and eyelets 7 preferably constitute the pivots of said links for a purpose which will herein-after appear.

The rods 1 and 2 are connected by ornamental fabric 8 which may be secured to the rods in any desired manner. I have illustrated said fabric as having hems 9 at its ends to receive the rods, but I am not limited to this particular fastening means. The

upper and lower edges of the fabric are connected to the links 5 by suitable lacings 10. These lacings are extended through opening 11 in the arms, and are laced backwardly and forwardly through openings 12 in the fabric, and through the eyelets 7 constituting the pivots of the links with the ends of the lacings tied together. By reason of this construction, the links can pivot or fold without tearing or injuring the fabric.

When the links 5 fold as indicated in dotted lines in Fig. 1, rod 2 is drawn toward rod 1, and the screen will occupy but very small space. To securely lock the parts in this folded position, I provide on one of the upper links 5, a lug 13 which is adapted to be engaged by the hooked end 14 of a sliding lock 15. This sliding lock 15 is provided with integral studs 16 mounted to slide in a slot 17 in the other link 5, and secured by screws 18 having heads thereon of greater diameter than the slot 17.

A knob 19 is provided on the locking slide to facilitate its manipulation. When the parts are folded together, this slide 17 may be moved longitudinally to lock its hooked end 14 over the lug 13 as shown in Fig. 3, so that the parts cannot swing to open position, but are securely held.

When the screen is drawn to its full open position across the window illustrated at 20, it may be held by an ordinary string 21 secured to the rod 2, and wrapped around a button 22 on the window frame. By means of a construction of this kind, the screen may be placed across the window so as to shield the occupants of the room from the gaze of those on the outside, and when the screen is not desired, it may be folded and locked in folded position either left supported in the eyes 3 or entirely removed as desired.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A screen of the character described, comprising two rods, links pivotally connecting the rods, flexible material connected to the rods and to the links, and one of said

2 rods longer than the other and adapted to be pivotally connected to a support, substantially as described.

2. A screen of the character described, comprising two rods, pivoted links connecting the rods, flexible material connected to the rods and to the links, a lug on one of said links, and a sliding lock on another of said links having a hooked end adapted to engage said lug and lock the links together when said links are moved side by side, substantially as described.

3. A screen of the character described, comprising two vertical rods, one rod longer than the other, devices receiving the ends of the longer rod and providing rotary mounting therefor, links pivotally connected to the rods and to each other, flexible material connected to the rods and to the links, a lug on one of the upper links, a sliding lock on the other of the upper links, said lock having a hooked end adapted to engage over the lug when the links are folded together, substantially as described.

4. A screen of the character described, comprising two vertical rods, a pair of pivoted links connecting the rods adjacent their upper ends, a second pair of pivoted links connecting the rods adjacent their lower

ends, a sheet of flexible material connected at its ends to the rods, lacings connecting the upper and lower edges of the flexible material to the links, and means for locking one pair of said links in folded position, substantially as described.

5. A screen of the character described, comprising two vertical rods, a pair of pivoted links connecting the rods adjacent their upper ends, a second pair of pivoted links connecting the rods adjacent their lower ends, a sheet of flexible material connected at its ends to the rods, lacings connecting the upper and lower edges of the flexible material to the links, means for locking one pair of said links in folded position, said means comprising a lug on one of said links, and a lock on the other of said links, said lock movable in a slot in said last-mentioned link and having a hooked end adapted to engage over said lug, substantially as described.

In testimony whereof I have signed my name to this specification in the presence of two subscribing witnesses.

ROSE HEILLER.
